UNITED STATES PATENT OFFICE.

TRIMBLE DE ROODE, OF NEW YORK, N. Y.

MINING APPARATUS.

1,229,418.

Specification of Letters Patent. Patented June 12, 1917.

Application filed December 29, 1911. Serial No. 668,410.

To all whom it may concern:

Be it known that I, TRIMBLE DE ROODE, a subject of the Queen of the Netherlands, residing in the city, county, and State of New 5 York, have invented certain new and useful Improvements in Mining Apparatus, of which the following is a full, clear, and exact description.

My invention relates to an improved apparatus to be used in connection with mining, and particularly in connection with a new method of mining set forth in detail in my companion application Serial No. 668,411.

15 In the drawings,

Figure 1 is a horizontal section illustrating conventionally the first step of my improved process.

Fig. 2 is a vertical section of the same.

20 Figs. 3, 5, 7, 9, 11 and 13 are horizontal sectional views of progressive steps.

Figs. 4, 6, 8, 10, 12 and 14 are vertical sectional views of Figs. 3, 5, 7, 9, 11 and 13, respectively.

25 Fig. 15 is a relatively enlarged detail view, conventional in character, of the shield or bulkhead and some of the apparatus therein employed in carrying out my improved method.

30 Fig. 16 is a side elevation, partly in section, of the same apparatus, certain parts being omitted, or not seen.

Fig. 17 is a plan view with the shield partly in section, on a horizontal plane.

35 Fig. 18 is a front elevation of the same apparatus partly in section.

At the outset I will describe in a general way my improved method of mining which comprises forming a cut in the material to 40 be mined; placing therein a suitable shield or bulkhead having in advance thereof a working space fitted with suitable apparatus for performing the mining operation; advancing said bulkhead or shield and 45 forming an outlet passage to the rear thereof of less cross sectional area than the cross sectional area of the said working space and directing said shield in any desired course through the material to be excavated.

50 As shown in the drawings, Figs. 1 to 14, such an apparatus may be caused to traverse completely a large tract of mining material, the shield being turned and started upon a reverse course by applying more 55 pressure to one side thereof than to the other

and that part of the material actually removed to the surface represents a very small part of the material actually mined or operated on since the major part of said material is deposited behind the advancing 60 shield; the minor part of said material, for example the coarser part, is removed through the primary outlet passage to a point outside of the entrance to the mine. Such a process is of material value when 65 employed in an anti-debris section wherein there are objections to discharging from the mine the finer debris that tends to operate as a nuisance. The apparatus herein described comprehends such means as is necessary to extract the values of the material and separate and manipulate the balance in the manner heretofore referred to.

70 In the drawings, 7 represents the ladder of a digger which constitutes the preferable 75 means for the main excavating work. This ladder is hinged at 7^a and may be provided with a suitable number of mechanically actuated excavating buckets 7^b. 7^c—7^d are levers pivotally connected together, the former being also connected to the ladder 7, the latter being also pivotally mounted at 7^e. 7^f is a chain suitably driven and connected with the levers 7^c—7^d to elevate the ladder 7. The entire digger thus described is mounted 85 on a suitable carriage which is arranged to traverse a track 7^g whereby said carriage may be moved transversely within the shield or bulkhead and so that the ladder 7 or digger will have the widest possible range of 90 movement. The various details of construction for operating and driving the latter may be modified in a variety of ways unnecessary to describe herein. 8 conventionally represents a separating device for the 95 excavated material while 14 represents a convenient pipe to convey the material excavated by the digger 7 to said separating device 8. 9 represents conventionally a refining apparatus. 10 conventionally represents a sluice-way. 11 represents one end of a casing which constitutes one end of the primary passage which enters the bulkhead from the rear. In the preferred form the casing 11 enters the rear of the bulkhead 105 at one side of the center, as best seen in Fig. 17, and means 11^a is provided whereby the point of elevation where said casing enters said shield or bulkhead may be varied as emergencies require. 12 is a discharge pipe 110

through which the material to be restrained is passed from the inside of the shield or bulkhead to a point outside of and to the rear thereof. 13 is a pipe which enters the shield from the rear, the purpose of said pipe being to drain such excess water as may be contained in the restrained material at the rear of the bulkhead, said drain pipe 13 leading, for example, to the sluice box 10, as shown. 15 represents what may be termed a packing or gland of any suitable construction arranged externally of the shield, the function of which is to prevent any excess of material to the rear of the bulkhead from leaking forward of the bulkhead or shield. 16-16 are independently operable cutting lips suitably mounted at the front of the shield or bulkhead and arranged to be forced ahead into the material to be excavated or in the path of movement of the edge of the shield. Means for forcing said lips ahead may comprise hydraulic rams 16^a. 17 conventionally represent driving wheels which may be of any suitable form and which are power driven, as by a ram 17^a, the function of said wheels being to advance or aid in advancing the shield. 18 are hydraulic nozzles arranged to swing as shown adjacent to the lips 16 to facilitate cutting away the material to be excavated in front of said lips. 19 represents a hydraulic supply pipe which communicates with any suitable source of power, for example, outside of the mine, said supply pipe 19 leading through the primary passage within the casing 11. The shield or bulkhead referred to is constructed in the main preferably of two main parts; namely, a lower part 20 which is U-shaped in horizontal cross section, and an upper part or roof 21 which surrounds the lower part 20 and overstands the same to form a roof to support the top wall or ceiling, thereby affording a thoroughly protected working space within said shield or bulkhead, open at the front for the work of excavating. 22 is a low secondary bulkhead which extends across the front of the lower part 20 of the bulkhead, the function of said secondary bulkhead being to protect the floor of the working space against any inrush of water or material; for example, in the event of a cave-in. The advantage of forming the shield or bulkhead of two sections 20-21 is apparent since in some instances it might be desirable to work the cut to a higher or lower elevation, in which event the upper section 21 of the bulkhead or shield may be elevated or depressed in a horizontal plane, said parts being slidably mounted one on the other and equipped with any suitable jacking means such, for example, as a hydraulic jack conventionally shown at 23. Suitable packings 24 may, of course, be provided between the overlapping

portions of the shield members 20-21. Likewise suitable packings 24 may be provided for the adjustable entrance at the rear of the bulkhead for the casing 11 of the primary entrance and exit passage. As shown in Fig. 17, the broadest part of the shield or bulkhead is at the front end, the sides thereof converging toward the rear, the purpose being to make it possible to readily alter the direction or course of the shield as the work progresses. The preferable line of convergence of one side of the bulkhead is preferably upon an arc having its center at the opposite front edge of the bulkhead. The several lips 16 are provided with any suitable bearings; for example, anti-friction rollers 16^b, see Fig. 17.

In the specification I have used the terms "bulkhead" and "shield" and in order that the distinction may be clearly understood and for the purposes of intelligently reading the following claims, it should be understood that by the term "bulkhead" I mean a means to stand to the rear of the line of work to advance therewith at a proper distance therefrom to furnish a proper adequate space. By the term "shield" specifically, I mean means which primarily supports the overhead material and which may be so constructed as to extend to the rear of the working space so as to also perform the function of the bulkhead aforesaid. Either and both of these means constitute protecting means to prevent material from flowing into or falling into the working space.

By the term "walls" as used, I intend to include either the top, rear, or side walls.

What I claim is:

1. In an apparatus for mining, protecting means forming a working space open at the front, means for transferring and depositing to the rear of said protecting means a portion of the material excavated, means for restraining said material at the rear of said protecting means, said restraining means having an outlet passage communicating with the rear of the working space, and means for transferring a portion of the excavated material through said passage.

2. In an apparatus for mining, a protecting means forming a working space open at the front, means for transferring a portion of the excavated material from the working space to and depositing the same at the rear of said protecting means, means for restraining said deposited material, said last mentioned means having a passage therethrough, and means extending through said passage for transferring from said working space the balance of said material.

3. In an apparatus for mining, a protecting means furnishing a working space therein open at the front and arranged to be advanced and including a rear bulkhead, means for excavating in front of said bulkhead and

- transferring and depositing a portion of the excavated material in a wet state to the rear of and against the bulkhead to aid in progressively advancing the latter.
5. In an apparatus for mining, a protecting shield furnishing a working space open at the front for excavation, hydraulic means for cutting away the material at the front of the shield, said shield having a protected outlet at its rear of less cross sectional area than the cross sectional area of the working space within the shield, and hydraulic means for transferring a part of the material excavated and depositing the same directly behind the shield as the same is advanced, and for transferring a portion of said excavated material through said rear opening.
10. In an apparatus for mining, a movable shield open at the front having a rear outlet arranged at one side of the center thereof, means for excavating material in front of said shield, a protected passageway extending from said rear outlet, means for depositing excavated material at the rear of said shield and around said protected passage, and means for turning said shield in its direction of travel.
15. In an apparatus for mining, a movable bulkhead, means for excavating in advance of said bulkhead, means for transferring and depositing a part of the excavated material to the rear of and against said bulkhead to aid in advancing the latter, and means for turning said bulkhead in its path of travel, said bulkhead having an outlet passage extending through the deposited material.
20. In an apparatus for mining, a shield having a forwardly projecting cutting edge, the body of the shield to the rear of said cutting edge being contracted whereby the same may be turned in a substantially short circle.
25. In an apparatus for mining, a shield furnishing a working space therein and arranged to be advanced through the material to be mined, a plurality of independently movable cutting lips at the forward edge of said shield and a hydraulic nozzle carried by each lip near its forward end to cut away material in advance of said lip, said nozzle being mounted to swing.
30. In an apparatus for mining, a shield arranged to be advanced through the material to be mined and furnishing a working space therein, and a packing extending around the outer side of said shield to prevent the forward flow of liquid past said shield from the rear.
35. In an apparatus for mining, a movable shield arranged to be advanced open at the front end furnishing a working space, a digger at the front and within said shield comprising a manually controllable ladder having a plurality of movable buckets with means for changing the position of the forward end of the ladder vertically, said means including a halyard connected with the ladder near its outer end, and a link connected with said halyard at a point near but spaced apart from its forward end, and a pivotal mounting for the rear end of said link below said halyard.
40. In an apparatus for mining, a shield arranged to be advanced open at the front end and furnishing a working space within the same, a digging apparatus within said shield comprising a movable ladder having a series of buckets carried thereby, a track for said ladder extending transversely of the shield and a carriage thereon supporting said ladder, and means whereby the forward end of said ladder may be moved horizontally and vertically and whereby the buckets thereon may be propelled.
45. In an apparatus for mining, a movable shield open at the front and having a rear outlet arranged at one side of the center thereof, means for excavating material in front of said shield, a protected passage way extending from said rear outlet, and means for depositing excavated material at the rear of said shield and around said protected passage way.
50. In an apparatus for mining in a bore or cut, in combination, a bulk-head comprising transverse roof and base portions adjustable relatively to each other adapted to move toward the working face of the material to be excavated, and means adapted to deposit part of the excavated material in the bore or cut in rear of said bulkhead.
55. In an apparatus for mining in a bore or cut, in combination, a bulk-head comprising a transversely and longitudinally curved roof portion and a transverse curved base portion adjustable relatively to each other adapted to move toward the working face of the material to be excavated, and means adapted to deposit part of the excavated material in the bore or cut in rear of said bulkhead.
60. In an apparatus for mining in a bore or cut, in combination, a bulk-head comprising a transversely and longitudinally curved transverse gland adapted to contact with said bore or cut, and a transversely curved base portion, the said gland and said base portion being adjustable relatively to each other adapted to move toward the working face of the material to be excavated, and means adapted to deposit part of the excavated material in the bore or cut in rear of said bulk-head.
65. In an apparatus for mining in a bore or cut, in combination, a bulk-head adapted to be moved toward the working face of the material to be excavated, means adapted to deposit a portion of the excavated material in the bore or cut in rear of said bulk-head, and means whereby another portion of said

excavated material may be conveyed through said material deposited in said bore or cut, comprising a manway through said bulk-head and extending rearwardly thereof.

- 5 17. In an apparatus for mining in a bore or cut, in combination, a bulk-head adapted to be moved toward the working face of the material to be excavated, means adapted to deposit a portion of the excavated material in the bore or cut in rear of said bulk-head, and means whereby another portion of said excavated material may be conveyed past said material deposited in said bore or cut comprising a manway through said bulk-head and extending rearwardly thereof, provided with means adapted to establish a current of another portion of said excavated material through said manway.
- 10 18. In an apparatus for mining in a bore or cut, in combination, a bulk-head adapted to be moved toward the working face of the material to be excavated, means adapted to deposit a portion of the excavated material in the bore or cut in rear of said bulk-head, a manway extending rearwardly of said bulk-head, means whereby another portion of said excavated material may be conveyed past said material deposited in said bore or cut, comprising a passageway through said bulk-head and extending rearwardly thereof, and means adapted to establish a hydraulic current of another portion of said excavated material through said passageway.
- 15 19. In an apparatus for mining in a bore or cut, in combination, a bulk-head adapted to move toward the working face of the material to be excavated, said bulk-head having an opening, means adapted to deposit a portion of the excavated material in the bore or cut in rear of said bulk-head, means adapted to support a portion of said deposited material so as to form a manway and a passageway extending through said

deposited material connected with said opening in the bulk-head. 45

20. In an apparatus of the character described, in combination, means adapted to progressively excavate material of a mass to be mined thereby forming an opening in said mass, means adapted to cause a liquid current to convey a finer portion of the excavated material to a point in said opening spaced from the working face and to progressively deposit said conveyed material in a manner to refill said opening and form a working space between said deposited material and the working face, a movable bulk-head adapted to bar return of any substantial amount of said deposited material to said working space, and means adapted to remove a coarser portion of said excavated material from said opening. 55

21. In an apparatus of the character described, in combination, means adapted to progressively excavate material of a mass to be mined thereby forming an opening in said mass, a bulk-head adapted to be advanced as the excavation progresses and to be advanced relative to the advance of the working face to maintain a working space therebetween, means adapted to cause a liquid current to convey a portion of the excavated material to the rear of said bulk-head to effect the progressive deposition of said conveyed material in a manner to refill said opening to the rear of the bulk-head, the bulk-head being adapted to bar return of any substantial amount of said deposited material to said working space, means adapted to return the excess liquid to said working space, and means adapted to remove another portion of said excavated material from said opening. 60 70 75 80

TRIMBLE DE ROODE.
